US00D820184S

(12) **United States Design Patent** (10) **Patent No.:** **US D820,184 S**
Bucher et al. (45) **Date of Patent:** **** Jun. 12, 2018**

(54) **VEHICLE WHEEL**

(71) Applicant: **Ford Global Technologies, LLC**,
Dearborn, MI (US)

(72) Inventors: **George Bucher**, Dearborn, MI (US);
James Grake, Beverly Hills, MI (US)

(73) Assignee: **Ford Global Technologies, LLC**,
Dearborn, MI (US)

(**) Term: **15 Years**

(21) Appl. No.: **29/593,072**

(22) Filed: **Feb. 6, 2017**

(51) **LOC (11) Cl.** **12-16**

(52) **U.S. Cl.**

USPC **D12/209**
